CLAIM

The ornamental design for a light therapy face mask, as shown and described.

DESCRIPTION

FIG. 1 is a front, right and bottom perspective view of a light therapy face mask showing our new design;

FIG. 2 is a front view thereof;

FIG. 3 is a rear view thereof;

FIG. 4 is a left side view thereof, a right side view being a mirror image of the left side view;

FIG. 5 is a top view thereof;

FIG. 6 is a bottom view thereof; and,

FIG. 7 is a rear, right and bottom perspective view thereof.
